COLLAPSIBLE BABY BED

George A. Sole and Ethel T. Sole,
Traverse City, Mich.

Application October 25, 1948, Serial No. 56,354

2 Claims. (Cl. 5—99)

1

This invention relates to a crib for a baby, and more particularly to a crib which can be folded into a compact unit when not being used.

An object of the invention is to provide a baby's crib which is capable of being quickly opened and closed without the use of any tool.

Another object of the invention is to provide a baby's crib which can be collapsed or folded into a small unit so that it will occupy a very little space when not being used.

A further object of the invention is to provide a baby's crib which is extremely simple and inexpensive to manufacture.

Other objects and advantages will be apparent during the course of the following description.

In the accompanying drawings forming a part of this application, and in which like numerals are employed to designate like parts throughout the same:

Figure 1 is a side elevational view of the crib for a baby, according to the present invention;

Figure 2 is a plan view taken on the line 2—2 of Figure 1;

Figure 3 is a sectional view taken on the line 3—3 of Figure 1;

Figure 4 is a sectional view taken on the line 4—4 of Figure 2;

Figure 5 is a fragmentary sectional view taken on the line 5—5 of Figure 4;

Figure 6 is a fragmentary sectional view taken on the line 6—6 of Figure 4;

Figure 7 is a side elevational view showing the crib in collapsed or folded position;

Figure 8 is a side elevational view, with parts broken away and a section, showing the position of the floor when the crib is in collapsed position.

Referring in detail to the drawings, the baby's crib is preferably fabricated of wood and is rectangular in shape when extended, and comprises a pair of spaced, parallel, vertically-disposed flat end members 10 and 11. Arranged at each corner of the crib and secured to the end members is a vertically-disposed post or standard 12 having a caster wheel 29 on its lower end. A pair of horizontally-disposed spaced braces 13 are arranged contiguous to the inner surface of each of the end members 10 and 11 and extend between the complementary posts 12 and are secured to the latter. A vertically-disposed support member 16 is arranged longitudinally along the outer surface of each of the posts 12 and is secured to the latter, there being a plurality of slots 17 formed in the support members 16 for a purpose to be subsequently described.

2

A pair of vertically-disposed, spaced, parallel collapsible side walls 14 are provided for the crib, and each of the side walls is composed of diagonally-disposed bars 23 and 24, which are pivotally connected to each other at their junction by rivets 25 to constitute a lazy tongs assembly. The ends of the lazy tongs assembly are pivotally connected to the support members 16 by means of pins or rivets 18 which project through the slots 17 so that the lazy tongs can be moved from extended position (Figures 1 and 2) to the collapsed or folded position (Figures 7 and 8).

A guard rail 19 provided with a longitudinally extending groove 20 for receiving the upper ends of the lazy tongs assembly is adapted to be positioned along the upper ends of the lazy tongs assembly for covering the upper ends of the latter to afford protection to the child from the projecting upper ends of the bars 23 and 24 in the event the child attempts to climb out of the crib.

A steel strap 21 is arranged transversely across the bottom of the crib intermediate the ends of the latter, the strap 21 being provided with bent apertured ends 22 which are arranged between the lower ends of the bars 23 and 24 of the lazy tongs assembly. The rivet 25 of the lazy tongs assembly passes through the aperture in the ends 22 to thereby dependently support the strap 21. The strap 21 provides a support for the crib floor when the crib is in extended or operative position. The floor embodies a pair of sections 26 and 27 arranged in end-to-end relation and having their meeting ends hingedly connected together by a pair of hinges 28. The other ends of the floor sections 26 and 27 are hingedly connected by hinges 30 to the braces 13 which are secured to the end member 10 and 11. A pair of finger-engaging openings 31 are provided in the floor sections 26 and 27 for lifting the latter when the crib is to be collapsed or folded.

From the foregoing, it will be seen that a baby crib has been provided which is ideal for many purposes. The crib may be collapsed, Figures 7 and 8, and stored in a small apartment, or carried in an automobile. The crib is provided with casters 29 which permit the crib to be easily moved from one place to another. Further, a guard rail 19 covers the upper ends of the lazy tongs structure for preventing the child from injuring itself on the latter. The crib includes a steel strap 21 which extends below the transverse center of the floor and provides a support for the latter when the crib is being used.

As many embodiments may be made of this in-

ventive concept, and as many modifications may be made in the embodiment hereinbefore shown and described, it is to be understood that all matter herein is to be interpreted merely as illustrative and not in a limiting sense.

We claim:

1. In a baby's crib, a pair of vertically-disposed end members, a pair of vertically-disposed, spaced, parallel standards secured to each of said end members, a pair of vertically-disposed, spaced, parallel, collapsible side walls, each embodying a plurality of diagonally-disposed bars pivotally connected together at their junctures, extending between said end members and secured to said standards, a horizontally-disposed brace arranged contiguous to the inner surface of each of said end members and secured to the latter, a floor arranged below said side walls and embodying a pair of sections arranged in end-to-end relation, said floor sections being hingedly connected together adjacent their meeting ends, said sections having their other ends hingedly connected to said braces, a guard rail arranged along the upper ends of said bars for protecting the occupant of the crib from the latter, and a steel strap arranged transversely below said floor and secured to said side walls for supporting said floor when said crib is occupied.
2. In a baby's crib, a pair of end members, a pair of standards secured to each of said end members, a pair of collapsible side walls each

embodying a plurality of diagonally disposed bars pivotally connected together at their junctures extending between said end members and secured to said standards, a horizontally disposed brace arranged contiguous to the inner surface of each of said end members and secured to the latter, a floor arranged below said side walls and embodying a pair of sections arranged in end-to-end relation, said floor sections being hingedly connected together adjacent their meeting ends, said sections having their other ends hingedly connected to said braces, means arranged along the upper ends of said bars for protecting the occupant of the crib from the latter, and a strap arranged below said floor and secured to said side walls for supporting said floor when the crib is occupied.
